UNITED STATES PATENT OFFICE.

LEIF J. INGOLFSRUD AND WILLIAM H. SOULE, OF CONISTON, ONTARIO, CANADA.

APPARATUS FOR SEPARATING MAGNETIC MATERIAL FROM NONMAGNETIC MATERIAL.

Application filed February 9, 1925, Serial No. 7,861, and in Canada March 31, 1924.

Our invention has for its object a method and means (1) for separating magnetic material from nonmagnetic material, and (2) for separating magnetic material into various grades according to its magnetic properties.

The method consists of conveying material of various magnetic properties on a surface inclined sideways to its direction of travel and subjecting said material to magnetic attraction towards said surface so that its gravitational tendency to roll or slide off said surface is retarded by the increased friction due to the magnetic attraction, this retardation being proportional to the magnetic properties of the individual pieces of the material. By varying the inclination of the surface or the strength of the magnetic field or by varying both along the direction of travel of the material, pieces of different magnetic properties are made to roll or slide off the surface at different points. This may be accomplished by means of a belt mounted so as to present a gradual increasing incline, magnets mounted up to the underside of said belt, means for feeding material onto said belt and proper receptacles to collect the separated material.

In the accompanying drawings, similar reference symbols refer to similar parts throughout the several views.

Figure 1 is a side elevation of apparatus having gradual increasing inclination of the belt surface and uniform magnetic field.

Figure 2 is a plan of Figure 1, the feeding and collecting means not shown.

Figure 3 is a section on line 3-3, Figure 1.

Figure 4 is a side elevation of apparatus having gradual increasing inclination of the belt surface and a series of magnets of different strength.

Figure 5 is a plan of Figure 7, the feeding and collecting means not shown.

Figure 6 is a section on line 9-9, Figure 7.

Figure 7 shows an arrangement by which a gravity classification, preliminary to magnetic separation, may be made.

Figure 8 is a section on line 11-11, Figure 10.

Referring to Figures 1, 2 and 3, 12 is a pulley mounted on a shaft 13, carrying a driving pulley 14. 15 is a pulley mounted

12 and lying at an angle to the same. Shafts 13 and 35 are mounted in suitable bearings on a frame of convenient form not shown on drawings.

Upon pulleys 12 and 15 is mounted a belt 16 and due to the position of the pulleys, the belt will be twisted, giving a varying inclination of the belt surface. Underneath top portion of belt 16 is mounted an electromagnet 17 which is kept magnetized by a current from a suitable source 18. A hopper 20 is attached in a suitable manner to a feeder 21, which feeds the untreated material 22 onto belt 16, it being understood that any type of suitable feeder may be used.

Under the lower edge of belt 16 is mounted a series of suitable receptacles 23. These receptacles are intended to receive the material when it slides or rolls off the belt. Material having little or no magnetic properties will leave the belt first and fall into the first receptacles, while material having greater magnetic properties will adhere to the belt until the magnetic force is no more able to retain the same, when it will fall in any of the other receptacles, according to its magnetic properties.

Referring to Figures 4, 5 and 6, the pulleys 12 and 15 are mounted as described for Figures 1, 2 and 3 and magnets (24, 25, etc.) are mounted under the top part of the belt 16. The feeding of material to belt 16, the separation and collecting of the separated material and other details are similar to that described for Figures 1, 2 and 3.

Referring to Figures 7 and 8: Due to different shapes, weights and roughness of individual pieces, it may be necessary to first classify the material to be treated according to its tendency to roll or slide off an incline belt before it is fed to the magnetic separator. This is accomplished by mounting pulleys 32 and 31 and belt 30 in a similar manner to pulleys 12 and 15, and belt 16, as described for Figures 1, 2 and 3. No magnets are used under belt 30. Material requiring a small inclination of the belt to slide will fall into one receptacle. Material requiring a steeper inclination of the belt will slide into another receptacle and so on into their proper receptacles as they travel on the belt. In this way the material is separated into groups, each group having the tendency to slide or roll on the same incline, regardless of its magnetic property. Each group may

now be separated according to its magnetic properties.

What we claim as our invention and desire to protect by Letters Patent is:—

- 5 1. In a magnetic separator, an endless travelling belt, said belt being mounted to travel at a gradually increasing inclination sideways to its direction of motion, magnets mounted adjacent to the underside of the
- 10 belt, means for feeding the material to be separated on to the upper surface of said

belt, and means to gather the graded material as it falls from the belt.

2. An apparatus as claimed in claim 1 in which a series of magnets of different strengths are mounted beneath the belt.

In testimony of the foregoing, we have hereunto affixed our signatures, this 23rd day of December, A. D. 1924, at Sudbury, Ontario.

LEIF J. INGOLFSRUD.
WILLIAM H. SOULE.
